Archworth Martin

ATTORNEY

UNITED STATES PATENT OFFICE

GEORGE W. HUGHES, OF MONESSEN, PENNSYLVANIA

TUYÈRE

Application filed July 15, 1930. Serial No. 468,007.

My invention relates to tuyères and the method of installing the same, and more particularly to tuyères for use in blast furnaces and the like.

5 One object of my invention is to provide a tuyère of such form that it will be of longer life than various types of tuyères heretofore employed.

Another object of my invention is to provide a tuyère that can be readily installed, 10 particularly in the making of replacements.

Still another object of my invention is to provide an improved manner of replacing tuyères without the necessity of waiting until 15 the furnace has cooled.

One manner in which my invention may be practiced is shown in the accompanying drawings, wherein Figure 1 is an elevational view of my improved tuyère, looking at the 20 inner end thereof; Fig. 2 is a longitudinal sectional view of the tuyère; Fig. 3 shows a portion of a furnace wall with a tuyère in process of being pushed into place therein, and Fig. 4 is a similar view, but showing the 25 tuyère seated in its operative position.

The tuyère is indicated by the numeral 5 and is of the water-cooled type, the body of the tuyère being hollow, and it being provided with tapped inlet and outlet openings

30 6 in its outer end, through which the cooling water may be circulated in the usual manner.

In order that the use of the tuyère may be more conveniently explained, I show a portion of a furnace wall 7 having the usual 35 tuyère opening within which is placed a tuyère cooler 8, which may also be water-cooled in the usual manner.

The tuyère is provided with a series of 40 tongues or overhung flanges 9 at its inner end, the tongue portions being spaced a slight distance apart. The inner wall of the tuyère is extended as at 10, to provide a cylindrical or inwardly-tapered lip that is shown as concentric to the tongues 9. Refractory 45 material such as fire clay is introduced into the annular space between the wall 10 and the tongues 9, and is retained in place by the in-turned or beaded ends 11 of the tongues 9. Also, the slot-like spaces between the tongues 50 9 permit the air to be forced out when the re-

fractory material is being pushed into place against the inner end of the tuyère body.

My invention is of particular utility in the replacement of burned-out tuyères. When it becomes necessary to remove a tuyère, the 55 tuyère opening in the furnace wall is filled with fire clay or other refractory material 12 to prevent heated gases from flowing out through the tuyère opening and interfering with workmen engaged in replacing the 60 tuyère.

While this refractory material 12 is still plastic or soft, a tuyère is brought into the position indicated in Fig. 3, and pushed to the position shown in Fig. 4. The insertion of 65 the tuyère against the fire clay results in the space surrounding the extended portion 10 thereof being filled with the clay, as shown more clearly in Fig. 4, and the normal heat of the furnace will burn the clay to a 70 refractory condition.

That portion of the clay remaining within the tuyère body will be blown out or otherwise removed, while the clay contained within the space between the parts 9 and 10 will 75 protect the metal parts of the tuyère and prolong its life, and the circulating water will, of course, have a cooling effect on the refractory and prolong the life thereof.

The beaded ends of the tongues 9 also serve 80 as wearing surfaces for the material passing down through the furnace in front of and over the inner end of the tuyère.

While the invention has been described as applied more particularly to tuyères, it will 85 be understood that the inventive idea is applicable also to various other devices such as bosh plates and coolers.

I claim as my invention:—

1. A tuyère body having an inward extension which is shaped and positioned to cooperate with spaced tongues in providing an annular space, and tongues disposed circumferentially of and radially spaced from said extension for retaining refractory material 90 in said space, the tongues being spaced apart.

2. A tuyère body having an inward extension which is shaped and positioned to cooperate with spaced tongues in providing an annular space, and tongues disposed circum- 100

ferentially of and radially spaced from said extension for retaining refractory material in said space, the tongues being spaced apart, and having their ends inturned.

3. A tuyère body having an extended portion of annular form, and extensions spaced radially of said extended portion and laterally of one another, for retaining refractory material in said space, the extensions having beads formed on their inner ends.

4. The method of installing tuyères which comprises placing unhardened refractory material in a tuyère opening and inserting a tuyère having a refractory-retaining projection on its inner end through said material.

5. The method which comprises forcing a tuyère body having refractory-retaining projections at its inner end, into a mass of unhardened refractory material, incidentally to placing the said body into operative position in a furnace.

6. A device for use in furnace walls, comprising a metal member having a lip at its inner end for supporting a refractory, and inwardly-extending tongues carried by said body having laterally-turned ends positioned to retain a refractory in place on said lip, the said tongues being spaced apart.

In testimony whereof I, the said GEORGE W. HUGHES, have hereunto set my hand.

GEORGE W. HUGHES.
